[57] CLAIM

The ornamental design for a drinking mug, as shown and described.

DESCRIPTION

FIG. 1 is a top, left, front side perspective view of the drinking mug according to a first embodiment of the present invention;

FIG. 2 is a top plan view of the drinking mug of FIG. 1; FIG. 3 is a bottom plan view of the drinking mug of FIG. 1; FIG. 4 is a rear side elevation of the drinking mug of FIG. 1;

FIG. 5 is a left side elevation of the drinking mug illustrated in FIG. 1;

FIG. 6 is a front side elevation of the drinking mug of FIG. 1; and

FIG. 7 is a right side elevation of the drinking mug of FIG. 1;

FIG. 8 is a cross-sectional view of the drinking mug along line 8—8 of FIG. 2;

FIG. 9 is a top, right, front side perspective view of the drinking mug according to a second embodiment of the present invention;

FIG. 10 is a top plan view of the drinking mug of FIG. 9; FIG. 11 is a bottom plan view of the drinking mug of FIG. 9;

FIG. 12 is a front side elevation of the drinking mug of FIG. 9;

FIG. 13 is a right side elevation of the drinking mug of FIG. 9, with a left side elevation being a mirror image thereof; and

FIG. 14 is a rear side elevation of the drinking mug of FIG. 9.
